PC(57) **CLAIM**

The ornamental design for an electric discharge machine, as shown and described.

DESCRIPTIONFIG. 1 is a front, top, and right side perspective view of an electric discharge machine showing our new design;
FIG. 2 is a rear, top, and left side perspective view thereof;
FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The parts shown in the broken lines do not form part of the claimed designs.
